BRAKE HANGER BRACKET

David M. Light, Chicago, Ill., assignor to American Steel Foundries, Chicago, Ill., a corporation of New Jersey

Application October 29, 1938, Serial No. 237,604

14 Claims. (Cl. 188—209)

My invention relates to a brake hanger bracket for a railway car and more particularly to a novel arrangement of such a bracket designed to eliminate play between the parts including the hanger associated therewith, thus greatly reducing the wear.

It is well known that the major portion of the wear in a brake hanger and in the bracket from which it is supported is generally due to the vibration which develops between the parts. The necessary manufacturing tolerances which enable the parts to be fitted together originally requires a certain amount of play between the parts and this develops rapidly under service conditions. Numerous forms of wear plates have been devised in order that wear on the brake hanger bracket may be prevented, said wear plates commonly being renewable from time to time as necessary. Effort has also been made to provide against vibration such as above mentioned by means of the use of the springs designed to prevent vibratory movement between the parts.

I have devised a simple method of securing the parts which confines the wear to the engaging surfaces between the brake hanger and the wear plate itself and thus reduces to a minimum the wear occurring on such a structure.

The attached drawing shows embodiments of my invention wherein Figure 1 is a fragmentary side elevation of a truck structure incorporating my novel brake hanger bracket; Figure 2 is a top plan view thereof; and Figure 3 is a sectional view taken through the structure shown in Figures 1 and 2 and substantially as indicated by the line 3—3 of Figure 1, the wear pad being shown in bottom plan;

Figure 4 shows a further modification of my invention, the view being a side elevation corresponding generally to the view shown in Figure 1.

Describing more particularly the embodiment shown in Figures 1 to 3, the truck frame member 2 has the integrally formed brake hanger bracket 4, the juncture of the bracket with said member being reinforced by the substantially vertically arranged rib 6 which merges with the said member 2 and the top wall of the bracket. The bracket terminates in a jaw-like structure having the flaring top and bottom walls 8 and 10 and the integrally formed lateral walls 12 and 14, said lateral walls having front edges of arcuate form as indicated at 16, thus accommodating my novel form of two-piece wear plate comprising the top member 18 and the bottom member 20 abutting each other along the plane indicated at 22 (Figure 1). At the rear of said wear plate is formed

the opening 24 receiving the top member 26 of the loop-type hanger 28, the said top member being seated upon the lower portion 20 of the wear plate and having a snug fit as at 30 with the top portion 18 thereof. The bottom portion 20 of the wear plate has the guide flanges 32, 32 seating against the lateral edges of the bottom wall 10 of the jaw structure, thus serving as additional positioning means. Upon the bottom surface of said member 20 are secured the rubber pads 34, 34, said rubber pads being secured as at 36, 36 to said member 20 by means of lugs formed on said pads and forced into openings in the bottom wall of said member 20, said openings being of the form best seen at 38, 38 (Figure 15) with relatively small orifices, thus securing said pads in position on said wear plate member 20 after the lugs are forced through said orifices. Aligned openings are formed in the top and bottom walls 8 and 10 of the jaw structure and the upper and lower portions 18 and 20 of the wear plate are slotted for the reception of the securing bolt 40, said securing bolt being retained in position after assembly by the threaded nuts 42, 42.

In assembly the top and bottom portions of the wear plate may be positioned upon the top member of the hanger and thereafter forced into the jaw opening until the slots of the wear plate are aligned with the openings in the top and bottom walls of the jaw structure, thus permitting the retaining bolt to be mounted in position. In this operation the rubber pads 34, 34 will be compressed and after the securing bolt is in position will tend to expand, thus holding the parts in tight engagement with each other.

The modification shown in Figure 4 is generally similar to that in the modification just described as far as concerns the frame member 2, the bracket 4, the reinforcing rib 6 and the jaw structure with the flaring top and bottom walls 8 and 10 and the lateral walls 12 and 14 terminating in arcuate front edges 16 also in the form of the hanger 28 in the top member 26 thereof. The embodiment shown in Figure 4, however, differs from that previously described in the form of the wear plate generally indicated at 44 and comprising the top portion 46 and the bottom portion 48. Said top and bottom portions are generally similar in form to the top and bottom portions of the wear plate previously described except that each is provided with a pair of rubber pads as indicated at 50 for the top portion and 52 for the bottom portion of said wear plate. Said rubber pads are secured as at 54, 54 in the manner de-

5

scribed for the previous embodiment, but said top and bottom portions engage each other only as indicated at 56, being relieved as indicated at 58 and spaced apart at their rear ends as at 60 5 so that the top member 26 of the brake hanger 28 will be clamped therebetween with some slight compressive force as the rubber pads 50 and 52 are compressed in the operation of assembly 10 which is substantially similar to that previously 10 described with the same form of securing bolt 40. In this embodiment it will be apparent that I have provided an arrangement which will afford some resilience between the wear plate and the brake hanger jaw and so accommodate slight 15 movements of the brake hanger between the parts of said wear plate, said parts, however, being so arranged as to exert some slight compressive force against the top member, thereby preventing any chattering between the said parts and said 20 hanger. In this arrangement also it will be apparent that no wear will occur between the parts of the wear plate and the walls of the brake hanger jaw inasmuch as the engagement between these parts is through the before mentioned rubber pads. 25

It is to be understood that I do not wish to be limited by the exact embodiments of the device shown which are merely by way of illustration and not limitation as various and other forms of 30 the device will of course be apparent to those skilled in the art without departing from the spirit of the invention or the scope of the claims.

I claim:

1. In a brake hanger bracket, a jaw-like 35 structure having flaring top and bottom walls and lateral walls the front edges of which are arcuate in form, a two-piece wear plate positioned within said jaw, said pieces having engagement adjacent their outer edges and being 40 spaced apart rearwardly thereof to accommodate the top member of a loop-type brake hanger, resilient means secured to each of said pieces and serving to space each piece from the adjacent wall and to position said piece with respect 45 to said wall, and securing means for said parts in the form of a bolt extending through said walls and aligned slots in said pieces, said resilient means being compressed between said top and bottom walls on assembly of said parts 50 thereby urging said pieces into engagement with each other and into engagement with said top member and serving to retain all of said parts in close cooperation with each other.

2. In a brake hanger bracket, a jaw-like 55 structure having top and bottom walls and low lateral walls with arcuate front edges, a wear plate positioned within said jaw and comprising hook-like top and bottom portions forming clamping means about the top member of a 60 brake hanger, said portions being spaced from each other to permit each to engage said member on opposite sides thereof, resilient means secured to the top and bottom portions respectively of said wear plate and serving to space 65 said top and bottom portions from the top and bottom walls of said jaw and to position them with respect thereto, and securing means in the form of a bolt extending through aligned openings in said top and bottom walls and extending 70 through slots in said wear plate aligned with said openings, said resilient means serving to urge said clamping means against said top member and to retain said wear plate in tight engagement with the walls of said jaw.

3. In a railway car truck, a frame member

having an integrally formed brake hanger bracket terminating in a jaw-like structure having flaring top and bottom walls and lateral walls with arcuate forward edges, a two-piece wear plate seated therein and having a rear configuration substantially complementary to said edges and comprising top and bottom members engaging each other adjacent their forward ends and spaced from each other adjacent their rear ends to accommodate clamping, a loop-type brake 10 hanger having its top chord positioned between said members, resilient means secured to said wear plate and serving to space said wear plate from said bottom wall, and a retaining bolt securing said parts in assembled relationship, said 15 resilient means serving to urge said parts into tight engagement with each other and to prevent play therebetween.

4. In a brake hanger bracket, a jaw-like structure having top and bottom walls and low lateral walls with arcuate front edges, a wear plate positioned within said jaw and comprising hook-like top and bottom portions forming clamping means about the top member of a 20 brake hanger, said portions being spaced from 25 each other to permit each to engage said member on opposite sides thereof, resilient means secured to the top and bottom portions respectively of said wear plate and serving to space 30 said top and bottom portions from the top and bottom walls of said jaw and to position them with respect thereto, and securing means in the form of a bolt extending through aligned openings in said top and bottom walls and extending through slots in said wear plate aligned with 35 said openings.

5. In a railway car truck, a frame member having an integrally formed brake hanger bracket terminating in a jaw-like structure having flaring top and bottom walls and low lateral walls 40 with arcuate forward edges, a two-piece wear plate seated therein and having a rear configuration substantially complementary to said edges and comprising top and bottom members in abutment adjacent their forward ends and spaced apart rearwardly thereof to afford clamping 45 means for the top chord of a loop-type brake hanger seated therein, resilient means secured to said wear plate and serving to space said wear plate from said bottom wall, and a retaining bolt securing said parts in assembled relationship, said resilient means serving to urge said parts into tight engagement with each other and to prevent play therebetween.

6. In a railway car truck, a frame member 55 having an integrally formed brake hanger bracket terminating in a jaw-like structure having flaring top and bottom walls and low lateral walls with arcuate forward edges, a wear plate with top and bottom portions seated therein and having a rear configuration substantially complementary to said edges and comprising top and bottom members in abutment adjacent their forward ends and spaced apart rearwardly thereof to afford clamping means for the top chord of a 60 loop-type brake hanger seated therein, resilient means secured to said bottom portion and serving to space said bottom portion from said bottom wall, and a retaining bolt securing said parts in assembled relationship.

7. A brake hanger bracket having a jaw portion with top and bottom walls, a wear plate positioned within said jaw and having top and bottom portions with hook-like means at the rear thereof serving to clamp therebetween the 75

5 top member of an associated brake hanger, a securing bolt extending through aligned openings in said top and bottom walls and received in slots in said wear plate, and resilient means between said wear plate and each of said walls, said resilient means serving to urge said hook-like means into engagement with said top member and to space said wear plate from said walls while urging all of said parts in tight relationship to prevent vibratory wear therebetween.

10 8. A brake hanger bracket terminating in a jaw structure having top and bottom walls, a wear plate having top and bottom members in engagement with each other adjacent their forward ends and otherwise spaced apart, each of 15 said members having hook-like rear means co-operating with the top chord of an associated loop-type hanger, a securing bolt extending through openings in said walls and aligned slots 20 in said members, and resilient means secured to each of said members and serving to space said members respectively from adjacent walls and also to urge said members into engagement with each other adjacent their forward ends and into 25 engagement with said top chord adjacent their rear ends.

9. A brake hanger bracket terminating in a jaw structure having top and bottom walls, a wear plate having top and bottom members in engagement with each other adjacent their forward ends and otherwise spaced apart, each of 30 said members having hook-like rear means co-operating with the top chord of an associated loop-type hanger, a securing bolt extending through openings in said walls and aligned slots 35 in said members, and resilient means secured to at least one of said members and serving to space said member from the adjacent wall and to urge said members into engagement with each other adjacent their forward ends and into engagement with said top chord adjacent their rear ends.

10. In a brake hanger bracket, a jaw-like structure having flaring top and bottom walls and lateral walls the front edges of which are 40 arcuate in form, a two-piece wear plate positioned within said jaw, said pieces having engagement adjacent their outer edges and being spaced apart rearwardly thereof to accommodate the top member of a loop-type brake hanger, resilient means secured to each of said pieces and serving to space each piece from the adjacent 45 wall and to position said piece with respect to said wall, and securing means for said parts in the form of a bolt extending through said 50 walls and aligned slots in said pieces.

11. A brake hanger bracket terminating in a jaw structure having top and bottom walls, a wear plate having top and bottom members in engagement with each other adjacent their forward ends and otherwise spaced apart, each of 5 said members having hook-like rear means co-operating with the top chord of an associated loop-type brake hanger, a securing bolt extending through openings in said walls and aligned slots in said members, and resilient means between each of said members and the adjacent wall, said resilient means being secured to said members and serving to urge said members into engagement with each other and into engagement with said top chord.

15 12. In a brake hanger bracket, a jaw-like structure having flaring top and bottom walls and low lateral walls with arcuate forward edges, a wear plate of two pieces positioned within said jaw, each of said pieces having secured thereto resilient means spacing said piece from the adjacent wall and positioning said piece with respect thereto, said pieces abutting each other adjacent their forward edges and being spaced apart rearwardly thereof to accommodate the 20 top member of a loop-type brake hanger, and means for securing said parts in assembled relationship.

13. A brake hanger bracket terminating in a jaw structure having top and bottom walls, a wear plate having top and bottom members in engagement with each other adjacent their forward ends and otherwise spaced apart, each of 30 said members having hook-like rear means co-operating with the top chord of an associated 35 loop-type brake hanger, a securing bolt extending through openings in said walls and aligned slots in said members, and resilient means secured to at least one of said members and serving to space said member from the adjacent 40 wall and to urge said members into engagement with each other.

14. A brake hanger bracket terminating in a jaw structure having top and bottom walls, a wear plate having top and bottom members in engagement with each other adjacent their forward ends and otherwise spaced apart, each of 45 said members having hook-like rear means co-operating with the top chord of an associated loop-type brake hanger, a securing bolt extending through openings in said walls and aligned slots in said members, and resilient means between each of said members and the adjacent 50 wall.

DAVID M. LIGHT.
